SPEED EXHIBITING DEVICE

Emmanuel Christ Nicholides, Chicago, Ill.

Application December 11, 1942, Serial No. 468,683

5 Claims. (Cl. 264—1)

This application is a continuation-in-part of application Serial No. 246,320, filed December 17, 1938 and application Serial No. 262,650, filed March 18, 1939.

This invention relates to speed indicating and recording devices and has among its objects a device for producing an indication of the maximum speed reached by a moving body, such as a motor vehicle, retaining the maximum speed indication if the maximum speed is maintained during a predetermined period or distance of travel; and the combination of such indicating device with means for recording this maximum speed indication.

The foregoing and other objects of this invention will be best understood from the following description of an exemplification thereof illustrated in the accompanying drawings, wherein

Fig. 1 is a side view of the assembled speed indicating and recording device;

Fig. 2 is a front view of the device;

Fig. 3 is a top view of the device with the cover removed;

Fig. 4 is a vertical cross-sectional view of the device along the line 4—4 of Fig. 3;

Fig. 5 is a partial horizontal sectional view of the enclosed mechanism along the line 5—5 of Fig. 4;

Fig. 6 is a vertical sectional view along the line 6—6 of Fig. 5;

Fig. 7 is a horizontal sectional view of the cover structure along the line 7—7 of Fig. 6;

Fig. 8 is a detailed cross-sectional view of a portion of the cover structure along the line 8—8 of Fig. 7;

Fig. 9 is a top view of the operating key handle;

Fig. 10 is a front view of the operating key handle;

Fig. 11 is a detailed cross-sectional view of the printing mechanism along the line 11—11 of Fig. 6;

Fig. 12 is a detailed view of the indicator driving disc;

Fig. 13 is a detailed sectional view of the indicator ratchet wheel along the line 13—13 of Fig. 4;

Fig. 14 is a partial horizontal sectional view similar to Fig. 5 indicating another operating condition;

Fig. 16 is a detailed sectional view along line 16—16 of Fig. 15;

Fig. 17 is a similar view to Fig. 14 under different operating conditions;

Fig. 18 is a detailed view of the indicator driving disc follower along the line 18—18 of Fig. 17;

Fig. 19 is a vertical cross-sectional view along the line 19—19 of Fig. 17;

Fig. 20 is a detailed sectional view similar to Fig. 16 under different operating conditions;

Fig. 21 is a vertical end view of the reset pin operating cam;

Fig. 22 is a view similar to Fig. 21 showing the operating cam in its engaged position;

Fig. 23 is a detailed sectional view of the indicator locking wheel and retaining pawl under operating conditions similar to Fig. 21;

Fig. 24 is a view similar to Fig. 23 under the same operating condition as Fig. 22;

Fig. 25 is a partial vertical cross-sectional view of the indicator mechanism showing its coupling connection to an electrical switch for operating colored lights; and

Fig. 26 is a sectional view of the switch along the line 26—26 of Fig. 25 and the electrical circuit connecting it to a battery and series of lights.

Truck owners have learned that by controlling the maximum speed with which their trucks are driven, considerable savings are made as a result of the reduced consumption of gasoline and oil; and the reduced wear and tear on the vehicle. As a result, attempts have been made to control the maximum speed of trucks by means of speed governors.

Governors, however, have their limitations. A vehicle equipped with a speed governor is very dangerous, as its pick-up is too sluggish for safety in cases of emergency. At the same time, the governor does not control the speed of the vehicle while coasting, allowing the driver to speed the vehicle down grades.

This invention provides a device which indicates the speed acquired by a moving vehicle if the speed exceeds a certain maximum value and retains this indication if the higher speed is maintained for a short distance. As a result, the driver of the vehicle has available at all times the full power of the vehicle and may use it in emergencies or in passing other slow moving vehicles without the indication of the device being retained, while assuring that a record of the higher speed is made, if he travels at the higher speed for a predetermined excessive time or distance.

A recording mechanism in combination with the indicating device enables an inspector, at the end of a run by the vehicle, to make a permanent

record on a report ticket or paper, and to also reset the indicator back to zero position.

The foregoing features of the invention will be fully explained in connection with the following description of an exemplification thereof.

The exemplification of the invention shown in the drawings comprises a speed indicating device having a casing 20 of cast metal, for instance, provided with a mounting plate 21 suitably attached to ridges of the casing by means of screws 22. To the mounting plate 21 are attached by means of screws 23 and spacer posts 24, two additional mounting plates 25, 26 fitting the interior of the casing.

As shown in Figs. 4 and 5, on a governor shaft 30 journaled in bearings 31, 32, secured to the inward mounting plate 26, is mounted a centrifugal governor formed by weights 33 linked by links 34, 35 to two collars 36, 37 seated on the shaft 30, collar 36 being affixed to the shaft as by means of pin 39, and the other elongated collar 37 being free to slide on the shaft so that the centrifugal action of the governor weights 33 moves the collar 37 along the shaft toward collar 36 against the action of spring 40 to a position corresponding to the momentary speed imparted to the shaft 30.

On one end, the shaft 30 is provided with a squared portion 42 arranged for coupling to the end of a flexible shaft 43 by means of a coupling member 44 threadedly fitting over a nipple extending from the casing 20. The other end of shaft 30 is provided with a worm 45 which drives gear 46 (Fig. 5) engaging driving gear 47 of a clutch member 48 revolvably mounted on shaft 49 on which is slidably keyed a clutch member 50. On the upward end of clutch shaft 49 is mounted an arm 51, as by means of screw 52, so that when the clutch members 48 and 50 are in coupling engagement, the rotation of the governor shaft rotates arm 51 and a pin 53 projecting from the arm. The rotation of arm 51 and its pin 53 will be proportional to the rotation of the governor shaft, so that one revolution of the arm 51 will correspond to a predetermined distance traveled by the vehicle.

As shown in Figs. 4 and 5 illustrating the normal rest position of the parts, the slidable clutch member 50 is provided with a collar 54 engaged by the forked end of a supporting arm 55 suitably pivoted on pedestal 56, so that under the action of a biasing spring 57, the supporting arm 55 moves the clutch member 50 into coupling engagement with the gear driven clutch member 48 for rotating the control arm 51. By moving the arm 55 against the action of spring 57, the coupling engagement between the driving gear 47 and the clutch shaft 49 may be broken.

The momentary position of the longitudinally slidable collar 37 is determined by the speed of rotation imparted to the governor shaft 30 by the flexible shaft 43. The surface of the slidable collar 37 is provided with circular teeth which, as shown in Fig. 6, are arranged to engage a gear wheel 60 mounted on a shaft 61 supported between the mounted plates 25, 26, for turning, through the engagement of its gear 62 with gear 63, a vertically journaled shaft of an indicator driving disc 64 having a periphery provided with cam-like teeth 65. As a result, the angular position of the disc 64 corresponds at all times to the momentary speed imparted to the governor shaft 30 by the flexible shaft 43, which in turn corresponds to the speed of the vehicle with which the apparatus is associated.

As shown in Figs. 4, 5, 15 and 19, the indicator

driving or position disc 64 has a driving pin 66 arranged to engage a projecting lug 67 of an indicator wheel 68, which is fixed on a shaft 68' that is pivotally mounted in the upper mounting plate 21. As a result, the indicator wheel 68 will follow the rotation of the indicator driving disc or wheel 64 as it rotates clockwise for an increase in speed, and counter-clockwise for a decrease in speed.

The upwardly projecting end of the indicator wheel shaft 68' carries an indicator arm 70, which, as shown in Fig. 3, has a raised pointer portion 71 cooperating with a circular scale 72 having raised dial numerals 73 on which pointer 71 indicates the speed of the vehicle, the indicator wheel 68 and the pointer 71 forming thus a speed index member. The circular scale 72 may be formed of a metal channel 74 filled with lead or solder to which is fused a steel sheet 75, on which are formed raised scale numerals 73. The indicator arm 70 rides on a ball 76 which rolls over the underlying surface portion of the mounting plate 21 so as to reduce friction and provide a support for the indicator 70.

As shown in Figs. 4, 5, 6, 15 and 19, the indicator wheel shaft 68' is surrounded by two ratchet discs 78 and 79, assembled into one unit 80 and having a downwardly projecting pin 81 to form an indicator locking wheel which is pivotally mounted on a bearing member 82 secured to mounting plate 21. The indicator wheel 68 is elastically coupled to the indicator locking wheel 80 by a spiral spring 69 extending from the upper coupling lug 67' of the indicator wheel 68 to the hub of the indicator locking wheel 80, so that the spring 69 tends to maintain the coupling lug 67 of the indicator wheel 68 in driving engagement with the coupling pin 81 of the indicator locking wheel 80.

As shown in Figs. 4 and 5, the indicator wheel 68 and the locking wheel 80 form peripheral ratchets. The lower locking ratchet disc 78 is normally locked by a pivotally mounted retaining pawl 83 that is biased by spring 84. The pawl 83 is arranged to control the operation of pawl 85 by means of a spring 86 coupling the two pawls 83, 85, so that when pawl 83 is actuated against the biasing action of spring 86 to unlock the lower locking ratchet disc 78, the other pawl 85 is actuated through spring 86 to engage and lock the indicator ratchet wheel 68, the two pawls 83, 85 being returned to the positions of Fig. 5 when the pawl 83 is returned to the locking position shown in Fig. 5. The upper locking ratchet disc 79 is locked by a pawl 88 biased by a spring 89 so as to lock the locking wheel 80 in the maximum speed position to which it is advanced by the indicator wheel 68 through the medium of the spiral coupling spring 69.

The several elements of the indicator driving mechanism are so arranged and designed that in the normal position shown in Figs. 4 and 5, the indicator wheel 68 will follow the motion of the indicator driving disc 64, while locking wheel 80 is prevented from moving in clockwise direction by pawl 83 and in counter-clockwise direction by pawl 88; and so that upon actuation of the pawls 83, 85 to the position of Figs. 17 and 20, in which the indicator wheel is locked against clockwise motion and the locking wheel is released so that it is free to be rotated in clockwise direction by the spiral coupling spring 69 until its pin 81 comes into engagement with the lug 67' of the indicator wheel corresponding to the maximum speed position of the indicator 70.

in which the locking wheel 80 is retained by pawl 88.

The operation of the rotary control arm 51, and the indicator ratchet 68 with its ratchet pawl 85, are controlled by a special control mechanism, one form of which will now be described in connection with Figs. 4, 5, 14, 15 and 17. It comprises a pivotally mounted clutch operating lever 90 having at its one end a hook-shaped cam member 92 cooperating with the cam pin 93 of an articulated clutch support extension 94 pivotally mounted on the upper end of the clutch support lever 55. The clutch operating lever 90 is so arranged that when it is moved from the position shown in Figs. 4, 5 and 17, against the biasing action of its spring 95 to the position shown in Fig. 14, its hook-shaped cam member 92 releases the cam pin 93 of the clutch support extension 94 and the clutch support 55, which is then pulled by its biasing spring 57 to the clutch coupling position shown in Fig. 15 in which the driving gear 47 is coupled to clutch shaft 49 for rotating the control arm 51; and that when the clutch operating lever 90 is returned by its biasing spring 95 from the position shown in Fig. 14 to the position shown in Figs. 4, 5 and 17, the cam hook 92 of the clutch operating lever 90 acting on pin 93 of the clutch support link 94 pulls the clutch support 55 so as to lift the clutch member 50 to the position shown in Figs. 4, 5 and 17, and break the coupling connection between the clutch shaft 49 and the clutch driving gear 47.

The clutch lever 90 is biased by its spring 95 to its normal clutch uncoupling position shown in Figs. 4 and 5, and is arranged to be locked by the engagement of its catch 91 with the hook 99 of a pivotally mounted latch lever 100 when the clutch lever 90 is tilted to its uncoupling position shown in Figs. 14 and 15, the latch lever 100 being biased by a spring 101 so that in the normal position, the outer hook side rests against the outer side of catch 91 of the clutch lever 90. The spring 95 has sufficient stored energy for actuating the clutch lever to return from the position of Figs. 14, 15 to the position of Figs. 4 and 5, and break the clutch coupling when the latch 100 is tilted against its biasing spring 101 to release the engagement of its hook 99 with the catch 91 of the clutch lever 90.

As shown in Figs. 5, 14, 17 and 18, there is also provided an actuating lever 105 pivoted at 106 and biased by spring 107 to press a follower 108 against the periphery of indicator driving disc 64. The follower 108 is pivotally mounted on the end of actuating lever 105 and biased by spring 109 toward a stop 110 so as to leave the actuating lever 105 unaffected when the indicator or driving disc 64 rotates counter-clockwise under conditions of decreasing speed; but to be actuated by cam teeth 65 of disc 64 when it rotates clockwise on an increase in speed, for tilting the actuating lever 105 into engagement with the adjacent arm of the clutch operating lever 90 so as to tilt it against the tension of its biasing spring 95 to release at its cam hook 92 the cam lock pin 93 of the clutch support lever 55 so that it may be pulled by its biasing spring 57 to its clutch coupling position shown in Fig. 15 in which the worm gear 45 rotates the control or delay action arm 51 in clockwise direction from the position shown in Fig. 5 in the direction of the arrow in Fig. 14, until, in the end position of its rotation, in moving from the position of Fig. 17 to the normal position of Fig. 5, it tilts

the end of the latch lever 100 out of its path against the tension of spring 101 while unlatching the clutch lever 90 from its latched position in Fig. 14.

5 The retaining pawl 83 of the locking ratchet disc 78, the clutch latch lever 100 and the rotary control arm pin 53 are so shaped and arranged that when the control arm 51 with its pin 53, in the course of the rotation, reach the dotted 10 line position of Fig. 17, the pin 53 trips the retaining pawl 83 to release the lower ratchet disc 78 and permit the indicator locking wheel 80 to be rotated by the tension of coupling spring 69 in a clockwise direction from its position shown 15 in Fig. 16 to that shown in Fig. 20. In addition, the counter-clockwise tilting motion of pawl 83 exerts a force on one end of a coiled spring 86 so that its other end forces pawl 85 against the toothed periphery of the indicator ratchet wheel 20 68 so as to lock it and prevent it from being advanced by the force exerted on its lug 67 by pin 81 of the released and advancing indicator locking wheel.

In the course of the further rotation of the 25 control arm 51 to the position shown in Fig. 17, the retaining pawl 83 is released and returned by its biasing spring 84 to its normal position shown in Figs. 4 and 14, locking the lower ratchet disc 78 and stopping further clockwise rotation 30 of the indicator locking wheel 80. The return of pawl 83 from the position of Fig. 17 to the position of Fig. 4, releases the external force on spring 86 which returns to position of Fig. 4 so as to disengage pawl 85 from indicator ratchet 35 wheel 68 and permit it to be advanced in a clockwise direction if its lug 67 is engaged by the pin 66 of the driving ratchet 64. On reaching the final position shown in Fig. 17, the lower portion of the rotary pin 53 trips clutch latch 40 lever 100 to release the clutch lever 90 and permit it to be returned by its biasing spring 95 to its normal position shown in Figs. 4 and 17, in which the driving gear 47 is uncoupled from the clutch shaft 49, thereby stopping the rotary motion 45 of the control arm 51.

The control mechanism described above in combination with the control arm 51 and the elastic coupling of the indicator ratchet wheel 68 to the indicator locking wheel 80 by the spiral coupling spring 69, form a delay action mechanism which locks the indicator 70 in a maximum speed position to which it was advanced after a predetermined delay, the delay depending upon a predetermined distance traveled by the vehicle, following a sudden increase of speed.

Although the entire cam-like periphery 65 of the indicator driving disc 64 may be provided with cam teeth for operating in the way described above over the entire speed range, the form of the invention applied to commercial vehicles such as trucks, may be provided with an indicator driving disc 64 having a cam surface arranged in the way shown in Fig. 12. The circular periphery of the driving disc 64 is shown provided with a section 115 without teeth which is engaged by the follower 108 while the speed of the vehicle is within one predetermined speed range, for instance, the low speed range between 0 and 20 miles; and a toothed peripheral portion 116 with which the 60 follower is maintained in engagement, covering the speed of above 20 miles. The peripheral section 115 has no cam teeth so that an increase in speed up to 20 miles has no effect on the operation of the control arm 51. The peripheral section 65 116 has teeth so spaced that each change of 5

miles, for instance, moves one tooth past the follower 108 for actuating the associated mechanism. As shown in Fig. 13, the lower ratchet disc 78 has also corresponding peripheral sections 117, 118, section 117 being equal in arc length to section 115 of indicator driving disc 65 and having no ratchet teeth, while section 118 is provided with teeth. As a result, the indicator locking wheel 80 which is coupled to the driving disc 64 by the coupling spring 69 follows the clockwise rotation of the indicator driving disc 65 as the speed of the vehicle is increased up to 20 miles, at which point the retaining pawl 83 freely riding on peripheral section 117 of the lower ratchet disc 78 engages the first tooth of peripheral section 118, thereby preventing further rotation of the indicator locking wheel 80.

As long as the speed of the vehicle is in the low speed range, corresponding to the peripheral section 115 of indicator driving or position disc 64 (Fig. 12) and section 117 of lower ratchet locking disc 78 (Fig. 13), the indicator driving pin 66 will advance the indicator ratchet wheel 68 and therethrough indicator 70; while the coupling spring 69 similarly advances the indicator locking wheel 80 to the maximum speed position reached within this range in which the indicator locking wheel 80 will be retained by retaining pawl 83 (Fig. 17). The follower 108 which is riding on the locking wheel 80 is not actuated in this range, and the clutch lever 90 remains in its normal uncoupling position shown in Fig. 17 so that the rotation of the governor shaft 30 does not in any way affect the control arm 51 which remains in the position shown in Fig. 5.

As soon as the speed of the vehicle is increased to a value higher than the low speed range, for instance, above 20 miles per hour, corresponding to the peripheral section 116 of the indicator driving disc 64 and section 118 of lower ratchet wheel 78, the operation of the mechanism will be as follows:

The indicator or position disc 64 with its driving pin 66 will engage the lower extension of lug 67 and advance the indicator position wheel 68 with the attached indicator 70 to the position indicating the momentary speed of the vehicle, while the upper extension 67' of lug 67 becomes disengaged from pin 81 of the indicator locking wheel 80, in the way shown in Fig. 16. Simultaneously, the first tooth of periphery 116 of the indicator driving disc 64 will actuate follower 108 to tilt actuating lever 105 against the arm of the clutch lever 90 until it releases the clutch support 55 so as to couple the clutch shaft 49 to the driving gear 47 and start the rotation of the control arm 51. When the rotating arm 51 brings its pin 53 to the dotted position 53' shown in Fig. 17, its pin 53 tilts pawl 83 and therethrough pawl 85, releasing locking disc 78 and locking indicator position wheel 68. As a result, indicator locking wheel 80 will, under the tension of the coupling spring 69 advance until its pin 81 again engages lug 67 in the way shown in Fig. 20 being retained in this maximum speed position by pawl 83. As the control arm advances further, its pin 53 trips latch lever 100 thereby releasing the clutch lever 90 and permitting its biasing spring 95 to return it from the coupling position of the clutch, shown in Fig. 14, to the uncoupled position shown in Figs. 4 and 17, thereby stopping the rotation of arm 51. In addition, the control pin 53 releases pawls 83 and 85 which are returned by their springs to their respective normal positions shown in Fig. 5, locking the indicator locking wheel 80 and pre-

venting its further advance, and releasing at pawl 83 the indicator position wheel 68 so as to allow it to be advanced to a higher speed indication while the engagement of its lug 67' with pin 81 of the locked indicator locking wheel 80 retains it in the maximum speed position to which it was advanced.

Should the speed of the vehicle be again increased, the procedure described above will be repeated. If the running speed of the vehicle is maintained during a complete revolution of the control arm 51 and if it is higher than the maximum speed on which the indicator locking wheel 80 is locked, then at the end of one revolution of the control arm 51, the indicator locking wheel 80 will advance to the new position where it will be retained. However, if the running speed of the vehicle is decreased to the maximum speed on which the indicator locking wheel 80 is locked, or to a lower speed, before the control arm 51 completes one revolution, the indicator locking wheel remains in the same locked position. As a result, the indication of the highest speed attained by a vehicle will be retained if the high speed is maintained during the predetermined traveled distance.

As shown in Figs. 1 to 4 and 9, all the elements of the speed indicating mechanism are mounted on, and are carried by the mounting plate 21, and constitute a self-supporting unitary device operative to indicate the maximum speed reached by the vehicle, the mounting plate 21 being secured to the open side of the casing 20 and having the index member 71 and the cooperating scale exposed on the exterior side of the mounting plate.

A speed indicating device of the type described above may be mounted on the dash-board of a car so that its indicator 70 with the scale 72 shall be exposed to view, being suitably enclosed, for instance, by a transparent cover of plastic material. An inspector provided with a standard camera would merely have to snap a picture of the indicator 70 and the scale 72, together with the vehicle identification S-100 in order to provide a conclusive record of the maximum speed the vehicle had acquired during its run, as indicated by the pointer on the scale.

A distinct phase of the present invention is the combination of a maximum speed indicating device of the foregoing type with a recording or printing mechanism arranged so as to make it possible to imprint a record of the maximum speed indication on simple duplicate slips of paper. In Figs. 1 to 4 and 6 to 11 is shown one form of a recording mechanism for enabling simple and quick recording of the speed indication, as well as identifying or other pertinent data that would be useful in establishing a permanent record of the maximum speed with which the particular vehicle traveled during a run.

In the form shown in the drawings, the recording mechanism is mounted in a cover member 125 which is secured to the casing 20 above the mounting plate 21. In a hollow cover compartment facing the indicator scale 72 is mounted a guide plate 126 held, for instance, by screws 127, and provided with guide grooves 128 for guiding arms 129 of a platen 130 movable in a direction towards indicator scale 72. The platen 130 is normally held in a raised position by helical springs 131 placed between guide arms 129 of the platen 130 and the underlying portions of the guide plate 126. Fitted properly and attached to

the platen 130 and facing scale 72 is a scale 132 made of a shell 133 having a steel sheet 134 with depressed numerals 135 fused thereto by a lead filling. Scale 132 is arranged to match scale 72 in such a way that when it is brought down against scale 72, the numerals 75 of scale 72 coincide and fit into numerals 135 of scale 132. In a shallow annular channel of platen 130 facing the path of pointer 71 of indicator 70, is seated a yieldable compressing ring 137, of rubber, for instance.

The cover member 125 is so shaped and arranged as to form a slot 138 between the exposed face of the mounting plate 21 with its scale 72 and the facing surface of scale 132, and of the platen 130, to permit insertion of a sheaf of one or more leaves of printing material 139 such as paper, into the space facing the scale 72 and the pointer 70. When the platen 130 presses the sheaves towards the indicator scale 72 and the pointer 70, a permanent record will be imprinted upon the sheaves, showing the maximum speed the vehicle had acquired during its run, as indicated by the pointer on the scale.

The actuating mechanism for the printing platen 130 comprises a shaft 140 having one end journaled in bearing 141 attached to the cover 125, and the other end attached to the inward end of a standard lock 142 secured to the top of the cover by means of screws 143, and having its operating end extending through the cover compartment; and an eccentric cam member 144 attached to the shaft 140 as by means of a press-fit. An operating handle 145 with a key-shaped extension 146 fits into the slot 147 of the outwardly projecting barrel of lock 142 for operating it. When the handle is turned, the eccentric cam 144 rotates and displaces the printing platen 130 forcing it against the sheaf of papers inserted into the slot 138 for performing a printing operation. Upon performing the printing operation, the printing platen 130 is automatically returned to its raised position by the springs 131, while at the same time under the biasing action of spring 148, the handle returns to its normal position from which it can be removed from the lock 142.

As shown in Figs. 6, 21, 22, 23 and 24, the actuating member of the recording mechanism simultaneously operates the indicator reset mechanism. The reset mechanism comprises a slidably mounted pin 150 extending through plate 126 and having a cam-shaped lower end arranged to engage the cam-like end of the pawl 88 which locks the indicator lock wheel 80. The upper end of pin 150 is provided with a cap-like head arranged to be engaged by cam arm 152 pivotally mounted on collar 151 attached to the end of shaft 140 and biased by a spring 154 against a stop pin 153. When the operating handle 145 is turned in the direction indicated by the arrow in Fig. 21, to perform the printing operation, cam arm 152 rides smoothly over the cap of pin 150, until the sheaf of paper are compressed, at which point under the biasing action of spring 154, it slips off the pin and comes to rest against the stop pin 153, in the dotted position 153' of Fig. 21. As the handle 145 is released, the shaft 140 with the collar 151 are returned by the biasing spring 148 to the normal position. In doing so, the collar 151 actuates the cam arm 152 to press the release pin in downward direction, and causes it to actuate the retaining pawl 88 to release the indicator locking wheel 80, which under the biasing action of spiral spring 89, will return the in-

icator 70 to zero indication. Cam arm 152 is then returned to its normal position shown in Fig. 21 by the pressure exerted on pin 150 by the biasing spring 155.

The maximum speed indicating and recording device described above may also be used for operating the usual speed indicator 160 which may, for instance, be mounted in one of the side walls of the casing and driven through gearing 161, 162 and 163 and 164 by the indicator disc driving shaft in the way shown in Figs. 4 and 25.

The speed indicating and recording device described above may also be used for operating a series of differently colored signal lights attached to the front and rear end of the vehicle. The purpose of these lights is to advertise the speed with which the vehicle is traveling, for instance, a green light may correspond to a speed of 20 miles or less, a yellow light to a speed of less than 30 miles, but more than 20 miles, and the red light to a speed of more than 30 miles. The use of these lights may have a psychological bearing upon the driver of the vehicle and cause him to keep to the speed within the allowable limits, as the lights will show all observers the speed with which the vehicle is traveling.

As shown in Figs. 25 and 26, a light control switch having an insulated disc 180 attached to mounting plate 26 and having electrical contact segments 181 is arranged to cooperate with a contact arm 183 driven by an extension of the indicator driving shaft 182. An electric cable 184 connects each contact strip 181 to a corresponding electric light bulb 185 and the storage battery of the vehicle, as shown in Fig. 26. As the indicator driving disc 65 is rotated to correspond with the running speed of the vehicle, the arm 183 contacts the corresponding strips 181 and thereby closes the circuit of its corresponding light.

In the speed measuring or indicating device described above as specific exemplifications of the invention, the speed measuring or index member is associated with locking means including a locking or follower member, such as represented by the ratchet wheels 80, which is arranged to be actuated after a predetermined time delay, represented, for instance, by a predetermined motion of the driving means to lock the measuring or index member in a position to which it was brought during a speed increase. In order to perform its function, the locking means embody retaining means in the form of pawls, for retaining the locking or follower member in the locked position, as well as biasing means, represented by the spring 69, for urging the measuring member to assume the position corresponding to the position of the follower locking member, as well as preventing means in the form of pawls and the coupling mechanism, for preventing the locking or follower member from following the motion of the measuring member upon the occurrence of a speed increase, and operative to eliminate the preventive action after a predetermined time delay represented by a predetermined motion of the driving means.

Various other mechanisms and arrangements than those described above in connection with specific exemplifications of the invention will suggest themselves to those skilled in the art for speed measuring and recording mechanisms operating in accordance with the principles of the invention. It is accordingly desired that in construing the breadth of the appended claims they shall not be limited to the specific details shown

and described in connection with the exemplifications of the invention.

I claim:

1. In a speed measuring device, from which, for example, a printed record of the speed indication of a moving body may be made: driving means moving at the rate of speed to be measured, means including a measuring member and means actuated by said driving means to move said measuring member to positions corresponding to its different speeds, locking means including a movable follower member arranged to follow the motion of said measuring member and operative to lock said measuring member in positions of different speeds, and control means operative upon the occurrence of a speed increase to exert a preventive action preventing said locking means from locking said measuring member in a position corresponding to said speed increase, said control means including means actuated after a predetermined timing action to eliminate said preventive action.

2. In a speed measuring device, from which, for example, a printed record of the speed indication of a moving body may be made: driving means moving at the rate of speed to be measured, means including a measuring member and means actuated by said driving means to move said measuring member to positions corresponding to its different speeds, locking means including a follower member arranged to follow in a predetermined manner the motion of said measuring member and to be locked in a position corresponding in a predetermined manner to a speed position of said measuring member, said locking means including means urging said measuring member to assume a position corresponding to the locked position of said follower member, and control means operative to exert a preventive action preventing said follower member from following the motion of said measuring member and arranged to be actuated after a predetermined timing action following the attainment of a speed in excess of a predetermined magnitude to eliminate said preventive action.

3. In a speed indicating device, from which, for example, a printed record of the speed indication of a moving body may be made: driving means moving at the rate of speed to be indicated, means including an index member and means actuated by said driving means to move said index member to positions corresponding to its different speeds, locking means including a follower member arranged to follow in a predetermined manner the motion of said index member and to be locked in a position corresponding to a speed position of said index member and operative to bring said index member to a position corresponding to the locked position of said follower member, said locking means including

retaining means for retaining said follower member in a locked position, and control means including a movable preventing member actuatable to exert a preventing action preventing said follower member from being retained in a locked position upon the occurrence of a speed increase and means including a movable restoring member actuated after a predetermined time delay action following the attainment of a speed in excess of a predetermined magnitude to eliminate the preventive action of said preventing member.

4. In a speed indicating device, from which, for example, a printed record of the speed indication of a moving body may be made: driving means moving at the rate of speed to be indicated, means including an index member and means actuated by said driving means to move said index member to positions corresponding to its different speeds, locking means including a follower member arranged to follow in a predetermined manner the motion of said index member and to be locked in a position corresponding to a speed position of said index member and operative to bring said index member to a position corresponding to the locked position of said follower member, said locking means including retaining means for retaining said follower member in a locked position, and means actuated by the motion of said driving means for eliminating the retaining action of said retaining means after a predetermined time delay action following the attainment of a speed in excess of a predetermined magnitude and for restoring the retaining action after said follower member is advanced to a position of higher speed.

5. In a speed indicating device, from which, for example, a printed record of the speed indication of a moving body may be made: driving means moving at the rate of speed to be indicated, means including an index member and means actuated by said driving means to move said index member to positions corresponding to its different speeds, locking means including a follower member arranged to follow in a predetermined manner the motion of said index member and to be locked in a position corresponding to a speed position of said index member and operative to bring said index member to a position corresponding to the locked position of said follower member, said locking means including retaining means for retaining said follower member in a locked position, control means operative to exert a preventive action preventing said follower member from being retained in a locked position upon the occurrence of a speed increase and actuated after a predetermined timing action to eliminate said preventive action.

EMMANUEL CHRIST NICHOLIDES.
